DECANTER OR SIMILAR ARTICLE

Ernest L. Du Pree, Weston, Conn., assignor to
Schenley Industries, Inc., New York, N. Y., a
corporation of Delaware

Application September 16, 1953, Serial No. 26,823

Term of patent 14 years

(Cl. D58—6)

To all whom it may concern:

Be it known that I, Ernest L. Du Pree, a citizen of the United States of America, residing at city of Weston, county of Fairfield, and State of Connecticut, have invented a new, original, and ornamental Design for a Decanter or similar article, of which the following is a specification, reference being had to the accompanying drawing, forming part thereof.

Figure 1 is a side elevational view of a decanter, or similar article embodying my new design. The opposite side, not shown, is substantially the same;

Figure 2 is an end elevational view thereof with the line pattern omitted from both sides for convenience of the illustration; and

Figure 3 is a sectional view thereof, as seen on the line 3—3 of Figure 1.

I claim:

The ornamental design for a decanter or similar article, as shown and described.

ERNEST L. DU PREE.
